Fig. 4.

Fig. 3.

Fig. 7.

Fig. 8.

Fig. 6.

FIG. 1 is a perspective view of the front and left side of an electric shaver showing my new design;

FIG. 2 is a perspective view of the electric shaver of FIG. 1 showing in particular the rear of the shaver;

FIG. 3 is an elevational view of the left side of the shaver of FIG. 1;

FIG. 4 is an elevational view of the front of the shaver of FIG. 1;

FIG. 5 is an elevational view of the right side of the shaver;

FIG. 6 is an elevational view of the rear of the shaver;

FIG. 7 is a top plan view of the shaver appearing in FIG. 4; and

FIG. 8 is a bottom plan view of the shaver as seen in FIG. 4.

In FIGS. 2 and 6 it is understood that the cutter teeth omitted for convenience of illustration are continuous in the paths indicated by the dot-dash lines.

I claim:

The ornamental design for an electric shaver, substantially as shown and described.
